NESTING COUNTING MEMBER FOR ELEMENTARY ARITHMETIC INSTRUCTION

Charles E. Jones, Evanston, Robert H. Crowle, Mount Prospect, and William G. Crowle, Deerfield, Ill., assignors of one-half each to Science Research Associates, Inc., a corporation of Delaware and Western Publishing Company, Inc., a corporation of Wisconsin, both of Chicago, Ill.

Filed Apr. 29, 1963, Ser. No. 74,651

Term of patent 14 years

(Cl. D25—1)

FIGURE 1 is a side elevational view of a nesting counting member for elementary arithmetic instruction showing the design;

FIGURE 2 is a top plan view;

FIGURE 3 is a bottom plan view; and

FIGURE 4 is a longitudinal sectional view taken along the line 4—4 of FIGURE 2.

We claim:

The ornamental design for a nesting counting member for elementary arithmetic instruction, as shown.
